Inventor:

William J. Walsh
By John H. Hendry
His Attorney.

UNITED STATES PATENT OFFICE.

WILLIAM J. WALSH, OF HAMILTON, ONTARIO, CANADA.

ROTATABLLE OPEN-BOOK REST.

1,093,220.

Specification of Letters Patent. Patented Apr. 14, 1914.

Application filed October 21, 1912. Serial No. 727,054.

To all whom it may concern:

Be it known that I, WILLIAM J. WALSH, a subject of the King of Great Britain, and resident of Hamilton, in the county of Wentworth and Province of Ontario, Canada, have invented new and useful Improvements in Rotatable Open-Book Rests, of which the following is a specification.

My invention relates to an open book rest, 10 rotatable in opposite directions on a table or desk, and of the kind shown in my United States Patents Nos. 1017120, and 1017121, dated February 13, 1912.

The objects of my invention are, to afford facilities whereby persons sitting at opposite sides of a table or desk may use the book rest as convenience permits, also to provide means for supporting the book rest and to 20 allow the same to be rotated in opposite directions. I attain these objects by the mechanism illustrated in the accompanying drawing in which:—

Figure 1 is a side elevation of an open book rest in readable position secured to a table and adapted to be rotated thereon. Fig. 2 is a front elevation of a portion of the same, showing the vertical hollow, or tubular, supporting shaft, broken, and the 30 horizontal telephone instrument holder, also broken. Fig. 3, is a plan of the casing together with the book rest arm which is shown broken, and the horizontal disk its supporting arm shown broken. Fig. 4 is 35 a detail elevation partially in section, showing the hollow vertical shaft supported and rotatable in opposite directions in a bushing which is rigidly secured to a side of a desk or table.

Similar characters of reference refer to 40 similar parts throughout the several views.

In the drawing 2 is an open book, on a rest 3, supported on an arm 4, which is adapted to swing upward on the horizontal fulcrum pin 5, which extends through the horizontal 45 frame, or casing 6. The book and its rest are shown in broken lines, in Fig. 1, of the drawing, adjusted to a non-readable, or out of the way position, against, or in contact with, a vertical pad, or cushion 8, and similar to my United States patent referred to. The vertical pad 8, forms a part of the rear 50 vertical plate, or board 9, which extends up-

ward from the casing 6, and is integral therewith.

The arm 4, together with the open book 55 rest and other mechanism connected therewith, are operated, in combination with the casing, in a similar manner to my said United States Patent No. 1017121;—in this application however, the wall for rigidly securing the casing thereto is dispensed with.

The important feature in this invention is a vertical shaft 10, preferably of tubular construction, downwardly extending from the rear and central part of the casing 6, 65 and integral, therewith, and rotatable on a table or desk, and a distance above said table or desk.

12, is a horizontal table, or desk, shown broken, in Fig. 1, and having a hole 13 70 therethrough, in a convenient place to admit a bushing 14, rigidly therein, and 15 is a horizontal flange, of said bushing, resting on the table.

The vertical shaft 10, extends through the 75 bushing 14, the lower end of said bushing is threaded to receive a nut 16, having a concentric hole 17 through the bottom thereof, thereby forming a circular shoulder 18, on which the lower end of the shaft 10 80 rests. The hollow shaft 10, fits loosely in the bushing 14 and rotatable in opposite directions, and may be easily withdrawn therefrom.

The casing 6, is provided with an arm 20, 85 extending from one side thereof and rigid therewith, and preferably on the right-hand side and in proximity with the rear of said casing. 21, is a circular horizontal, or level disk on the end part of the arm 20 and rigid 90 therewith, and has a rim 22 around the same extending above the level, or upper face of the plate, to prevent a telephone instrument placed thereon from sliding off the plate. The casing 6, together with the shaft 10, the 95 open book rest, and the disk 21, are rotatable in opposite directions, as a convenience for a person or persons, sitting at a table, or desk. The opening 17, in the nut 16, communicates with the vertical opening 23, 100 in the hollow vertical shaft 10, which has an opening 24 through one side thereof communicating with the opening 23.

26 is an ordinary telephone cable, adapted

to extend through the opening 17 in the nut 16, and through the hollow shaft 10, and out through the opening 24 of said shaft, and connects with a common telephone instrument which may be on or off the circular disk 21.

When the open book rest is attached to a side of a table, or desk, as in Fig. 4, of the drawing, a flanged bracket bearing 19, having a vertical socket 25 is employed, said socket having a lower opening 27 for the cable 26 to pass through, and a shoulder 28 formed by the said opening 27 being smaller in diameter than the bore of the socket. The lower end of the hollow shaft 10 rests on the shoulder 28, and is adapted to rotate in opposite directions in the socket. The bracket 19 is rigidly secured to a side of a table or desk by means of screws 29 through the flange or flanges 30 of the socket.

The arrows shown in Fig. 3 of the drawing indicate the horizontal and opposite rotary directions to which the parts of the

device may be simultaneously rotated to position.

What I claim as my invention and desire to secure by Letters Patent, is:

In an open book rest, a casing, a tubular shaft extending downwardly therefrom and integral therewith, a table, or desk, a bushing extending through the table and beyond, and provided with an upper annular flange to rest solidly on the table, the end portion of the bushing screw threaded, and a nut provided with an annular flange abutting the underside of the table, and a shoulder in the nut, said nut having an opening concentric therewith, and with the shaft, and screwed on said end of the bushing, and said shoulder adapted to support the end of the shaft, and allow the shaft to be rotatable therein.

WILLIAM J. WALSH.
